UNITED STATES PATENT OFFICE.

WILLIAM DUNCAN, OF LOS ANGELES, CALIFORNIA.

FACIAL MASSAGE DEVICE.

Application filed August 20, 1924. Serial No. 733,170.

This invention relates to improvements in massaging devices.

It is an object of the invention to provide a massaging device consisting of a handle 5 with a pair of rotating rubber rollers or balls mounted upon the handle adapted to engage the face and in which the balls or rollers are so mounted as to conform with the contour or projections upon the face regardless of 10 the position of the handle of the device.

It is a further object of the invention to provide a massaging device consisting of a handle, a plurality of balls or rollers pivotally mounted with respect to the handle and 15 to provide means for urging the balls or rollers into a predetermined normal position with respect to the handle.

With the foregoing and other objects in view which will be made manifest in the following detailed description and pointed out in the appended claims, reference is had to the accompanying drawings for an illustrative embodiment of the invention, wherein

Fig. 1, is a view showing the improved 25 massaging device in one applied position.

Fig. 2, is a similar view to Figure 1, showing the improved massaging device in another applied position.

Fig. 3, is a top plan view of the massaging 30 device, parts being broken away and shown in sections.

Fig. 4, is a vertical section taken substantially upon the line 4—4 of Figure 3.

Referring to the accompanying drawings 35 wherein similar reference characters designate similar parts throughout, the device in its preferred form consists of a handle formed of a single piece of wire which is bent centrally of its length as at 10 to provide divergent portions 11 and 12 adapted 40 to co-operate with convergent portions 13 and 14 to form a grip. The portions 15 and 16 are slightly divergent and are bent to provide laterally extending portions 17 and 18 which co-operate with portions 19 and 20 45 to form a suitable yoke. The ends of the portions 19 and 20 are bent inwardly to provide pintles 21 upon which is pivotally mounted a fork 22. Within the fork 22 is 50 disposed a pair of rollers 23 and 24 which in the preferred form of invention are in the form of soft rubber balls which have bushings 25 and 26 extending therethrough.

The ball 24 has its bushing 26 rotatably 55 mounted upon a pin 27 mounted in the legs of the fork 22. The ball 23 has its bushing

25 disposed over the ends 21 of the portions 19 and 20 so that the ball 23 and the fork 22 are both rotatable upon the ends 21.

It is desired that the balls 23 and 24 be 60 urged into a predetermined position with respect to the handle so that regardless of the position actually taken of the handle with respect to the balls as the device is moved over the face, one of the balls will be pressed 65 gently against the face. To accomplish this, a clip 28 preferably formed of sheet metal is secured to the divergent portions 15 and 16 and to this clip is fastened one or more 70 elastic bands 29 which are connected to the back or crossed part 30 of the fork 22.

As shown in Figure 4, the plane of the fork 22 may assume an inclined position with respect to the handle, but is urged into such position by the elastic bands 29, that 75 it will tend to assume its normal position in the same plane as that of the handle.

As shown in Figure 2, when the device is passed over the cheek, the ball 23 which is pivoted to the handle, applies most of the 80 pressure. That is to say that when the fork 22 is in the same plane as that of the handle, the handle transmits most of the pressure directly to the ball 23.

In Figure 1, where the fork 22 is shown 85 as inclined with respect to the handle, most of the pressure will be exerted by means of the ball 24 because of the elastic bands 29 urging the fork into its normal position.

It is to be understood that both balls ordinarily engage the face simultaneously, but upon passing over a projection upon the face, one ball may exert more pressure 90 against the face than the other.

From the above it is seen that I have provided 95 a massaging device consisting of a handle, a fork pivoted in the handle, rotating elements rotatable within the fork, one of said elements being rotatable upon a portion of the handle, and that means is provided for urging the fork and the rotating elements 100 into a predetermined normal position with respect to the handle.

It is to be understood that various changes 105 in the details of construction may be made without departing from the spirit or scope of the invention as defined by the appended claims.

What I claim is:

1. A massaging device comprising a handle, a fork pivotally mounted upon said handle, a resilient rotating element rotatable 110

within said fork, said rotating element being pivoted upon said handle, resilient means adapted to urge said fork into a normal predetermined position with respect to said handle, and an additional massaging element mounted upon the fork remote from the axis of rotation of the fork.

2. A massaging device comprising a handle, a fork pivotally mounted upon said handle, a resilient rotating element upon said fork remote from the center of rotation of said fork and about an axis parallel to the axis of rotation of the fork, and yieldable means adapted to urge said fork into a predetermined position with respect to said handle.

3. A massaging device comprising a handle, a fork pivotally mounted upon said handle, a plurality of rubber balls rotatable within said fork about axes parallel to the axis of rotation of the fork, and means for

urging said fork into a predetermined position with respect to said handle.

4. A massaging device comprising a handle, a fork pivotally mounted upon said handle, a plurality of rubber balls rotatable within said fork about axes parallel to the axis of rotation of the fork, and means for urging said fork into a predetermined position with respect to said handle, said means including an elastic band secured to said fork and to said handle.

5. A massaging device comprising a handle, a fork pivotally mounted upon the handle, a plurality of resilient elements rotatably mounted upon said fork about axes parallel to the axis of rotation of said fork, and means for urging the fork into a predetermined position.

In testimony whereof I have signed my name to this specification.

WILLIAM DUNCAN.
